UNITED STATES PATENT OFFICE.

CHARLES E. CLEVELAND, OF FOND DU LAC, WISCONSIN.

DESIGN FOR A STREET-LAMP.

42,434.

Specification for Design.

Patented Apr. 30, 1912.

Application filed January 16, 1912. Serial No. 671,525. Term of patent 7 years.

To all whom it may concern:

Be it known that I, CHARLES E. CLEVELAND, a citizen of the United States, residing at Fond du Lac, in the county of Fond du Lac and State of Wisconsin, have invented a new, original, and ornamental Design for Street-Lamps, of which the following is a specification, reference being had to the accompanying drawing, forming part thereof.

In the drawings: Figure 1 is a perspective

view of the street-lamp; and Fig. 2 is a cross-section thereof, taken on the line 2—2 of Fig. 1, looking down.

I claim:

The ornamental design for a street-lamp, as shown.

CHARLES E. CLEVELAND.
